(57) **CLAIM**

The ornamental design for a visually stimulating animal toy, as shown and described.

DESCRIPTION

FIG. 1 is a perspective view of a visually stimulating animal toy showing my new design;

FIG. 2 is a top view thereof;

FIG. 3 is a front view thereof;

FIG. 4 is a bottom view thereof;

FIG. 5 is a rear view thereof;

FIG. 6 is an end view thereof; and,

FIG. 7 is an opposite end view thereof.

The broken lines are for purposes of illustration only and form no part of the claimed design.
